(57) **CLAIM**

The ornamental design for a ring as shown and described.

DESCRIPTION

FIG. 1 is a front view of the jewelry showing my new design with a rotatable center piece shown in a first rotational position;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a back perspective thereof;

FIG. 8 is a front perspective view thereof;

FIG. 9 is a front perspective view of the design shown in FIGS. 1-8, wherein the rotatable center piece is in a second rotational position;

FIG. 10 is a front perspective view of the design shown in FIGS. 1-8, wherein the rotatable center piece is in a third rotational position;

FIG. 11 is a front perspective view of the design shown in FIGS. 1-8, wherein the rotatable center piece is in a fourth rotational position; and,

FIG. 12 is a front perspective view of the design shown in FIGS. 1-8, wherein the rotatable center piece is in a fifth rotational position.

The appearance of the rotatable center piece of the jewelry sequentially transitions between the images shown in FIGS. 8-12. The process or period in which one image transitions to another image forms no part of the claimed design, and positions or movements as shown are not limited to any sequential order or any specific progression of movements or positions.

It is further to be understood that the design as disclosed may comprise elements and features in various embodiments that do not exhibit any movement or multiple positions, or comprising fewer than all disclosed movements or positions. The inclusion of all Figures is without prejudice as to the ability to present claims comprising individually disclosed features and to embodiments comprising fewer than all figures in this or any subsequent continuation, divisional or other related applications.

(Continued)

The broken lines shown in the drawings represent portions of the ring which form no part of the claimed design.
